United States Patent Office.

JOHN McMAHON, OF WOOSTER, OHIO, ASSIGNOR TO HIMSELF AND
BENJAMIN SCOTT, OF SAME PLACE.

Design No. 4,967, dated May 30, 1871.

DESIGN FOR CLAW-BARS.

The Schedule referred to in these Letters Patent and making part of the same.

I, JOHN McMAHON, of Wooster, in the county of Wayne and State of Ohio, have invented a new and improved Design for a Claw-Bar, of which the following is a specification.

Nature of the Invention.

The conformation of my claw-bar is fully shown in the accompanying drawing, in which—

Figure 1 is a front view of the said claw-bar.

Figure 2 is a side elevation of the same.

General Description.

The upper part of the bar, not shown in the drawing, is made of the customary tapering form, and is not here represented, because I do not claim any peculiarity therein.

The lower part, in which the claw or points A A and the heel or bearing B are formed, is made as repre-

sented, the cavity C, between the points A A, being cut out in the square form shown in fig. 1, in contradistinction to splitting, as usual with bars heretofore made.

A recess or cavity, D, is formed in the upper inner angle of each point or member of the claw for the purpose of receiving the head of the spike and preventing its slipping out.

The bearing B forms an arc or curve of increasing radius from the front backward, terminating in a projecting shoulder, E.

I claim—

The design for an improved claw-bar, as shown.

JOHN McMAHON.
